POST BINDER

Courtney C. Wall, Ozark Beach, Mo., assignor to
Helen Holman Wall, Ozark Beach, Mo.

Application September 10, 1942, Serial No. 457,823

6 Claims. (Cl. 129—12)

This invention relates to loose leaf binders of the type having sheet impaling posts, upon which posts is formed one element of a means for securing together the locking bar and said posts to hold the follower blocks in position where the loose leaf sheets in the binder are maintained in the form of a compact filler.

One of the primary aims of this invention is the provision of a post binder of loose leaf character, the parts whereof are constructed of inexpensive, easily procurable material obviating the necessity of employing metal springs, binder's board, canvas and metal parts, all accomplishing the result of presenting a strong, durable and satisfactory sheet holding device that may be inexpensively manufactured and created of materials not now vitally essential to the defense program.

A further object of the invention is to provide a loose leaf binder with a specially formed locking bar, capable of co-acting with a pair of posts, the inherent characteristics of which bar and posts permit manipulation to lock and unlock the binder as it becomes desirable to remove one of the covers for the placement or withdrawal of a portion of the filler.

Minor objects of the invention are most important since the same include specific details of construction respecting the manner of forming the locking bar, the posts, and the follower blocks, and therefore, a number of objects of lesser importance will be found in the following specification, referring to the accompanying drawing, wherein:

Fig. 1 is a top plan view of a post binder made in accordance with the present invention.

Fig. 2 is a side elevational view of the same.

Fig. 3 is a back view thereof, and

Fig. 4 is an enlarged detailed fragmentary sectional view taken on line IV—IV of Fig. 1.

The component parts of a post binder made in accordance with my invention, are substantially the same as those heretofore used in creating loose leaf equipment of that character and include two follower blocks 6 and 8, both of which have a cover 10 connected thereto by a hinge 12. Covers 10 and hinges 12 are similar in nature and therefore, interchangeable during the manufacture of the equipment. Follower blocks 6 and 8, as well as covers 10, are made of thin sheets of wood and if desired, may be ply-wood without covering.

The proximal edges of covers 10 and follower blocks 6 and 8, as the case may be, are grooved to receive the marginal edges of hinges 12. Said 55

hinges are formed of fabric and held in place by glue or cement strengthened, if desired, by transverse pegs 13. Bevelling of the edges of follower blocks 6 and 8 and certain edges of covers 10 may be desired, and if so, a milling operation will accomplish the result.

Follower block 6 has at least two spaced apart perpendicular posts 14, each rigidly anchored thereto through the medium of a cross pin 16 that is driven to position after one end of post 14 is introduced to the opening 18 formed in follower block 6.

Posts 14 receive sheets 20, the character of which is conventional. These sheets are punched with centers corresponding to the distance between the axes of posts 14, and therefore, when follower block 8 and the hereinafter described locking bar is lifted from posts 14, sheets 20 may be moved to and from their position in the filler.

Each post 14 is provided with teeth or serrations formed as shown in Fig. 4, to present a series of shoulders 22 beneath which a portion of locking bar 24 is engaged when the binder parts are operatively assembled. Shoulders 22 are preferably milled in the outer sides of posts 14. The proximal sides of posts 14 are smooth, and therefore, when posts 14 are flexed toward each other, the portions of locking bar 24 engaged beneath shoulders 22 are disengaged and bar 24 is easily lifted from a position against upper follower block 8.

In producing posts 14 a good grade of wood, hard enough to maintain shoulders 22 in good condition during use, must be employed and the material from which locking bar 24 is constructed should likewise be of a hard wood, suitable for engagement with shoulders 22 as shown in Fig. 4.

A tongue 26 is formed on locking bar 24 adjacent to each end thereof and within a perforation 28 through which a post 14 must pass when bar 24 is forced against block 8. Perforations 28 are at least as great in diameter as the diameters of posts 14 and when said posts are drawn toward each other, tongues 26 are out of engagement with shoulders 22.

Locking bar 24 is initially relatively thick but its central portion is longitudinally cut away as at 30 and its ends are similarly reduced in thickness to form spaced contact points 34 on the lower surface of the bar. The ends of bar 34 are thus spaced above the follower block 8 and this spacing, together with cavities 32 formed in the upper face of the block, permit insertion of the fingers of the operator between

the block and the ends of the bar for removing the latter when the upper ends of posts 14 are manually flexed toward each other to disengage tongues 26 of the bar from shoulders 22 of the posts.

Locking bar 24 has its points of contact 34 with follower block 8 adjacent to posts 14 and between the same to prevent any objectionable rocking action and to impart a holding action near the interlocked elements 22 and 26. Openings 19 in follower block 8 are slightly larger in diameter than posts 14, or of a size sufficient to allow the respective entering posts 14 to flex an amount capable of freeing tongues 26 and shoulders 22.

Shoulders 22 may be formed in the inner or proximal sides of posts 14 and the position of tongues 26 changed accordingly. In such arrangement, the posts are flexed from each other when the locking bar 24 is released. The outer faces of posts 14 are smooth and an upward force at the center of bar 24 will be ample to arch the same and thereby shorten the distance between the free ends of tongues 26. This, together with an outward flexing of the posts assures quick release.

The wooden parts of this binder may be finished as desired and combine to present a desirable assembly capable of meeting the requirements of loose-leaf post binders without employing expensive materials and manufacturing methods.

Having thus described the invention, what is claimed as new and desired to be secured by Letters Patent is:

1. In a binder of the character described, a pair of posts formed of relatively flexible material; a follower block provided with post-receiving openings; a locking bar having perforations therethrough to freely receive the posts respectively; and interlocking means formed on the posts and the locking bar to hold the latter in engagement with the former, said locking bar having a contact point thereon adjacent to each perforation for contacting engagement with said follower block, the portion of the locking bar intermediate said points and the portions of the bar from said points to the ends of the bar being spaced from the follower block.

2. In a binder of the character described, a pair of posts; a follower block provided with post receiving openings; a locking bar having perforations therein to receive the posts respectively; and interlocking means formed on the posts and locking bar to hold the latter in engagement with the former, said interlocking means being rendered inoperative when the posts are flexed toward each other.

3. In a binder of the character described, a pair of posts formed of relatively flexible material; a follower block provided with post-receiving openings; a locking bar having perforations

therein to freely receive the posts respectively; and interlocking means formed on the posts and locking bar to hold the latter in engagement with the former, said interlocking means comprising a series of transverse, spaced apart shoulders formed on the posts, and tongues integral with the locking bar, engageable successively with said shoulders and disengaged from the shoulders by flexing of the posts to vary the distance between the latter.

4. In a binder of the character described, a pair of posts formed of relatively flexible material; a follower block provided with post-receiving openings; a locking bar having perforations therein to freely receive the posts respectively; and interlocking means formed on the posts and locking bar to hold the latter in engagement with the former, said interlocking means comprising a series of transverse, spaced apart shoulders formed on the posts, and tongues integral with the locking bar, engageable successively with said shoulders, said tongues being within the perforations of the locking bar and disengaged from the shoulders by flexing of the posts to vary the distance between the latter.

5. In a binder of the character described, a pair of posts formed of relatively flexible material; a follower block provided with post-receiving openings; a locking bar having perforations therethrough to freely receive the posts respectively; and interlocking means formed on the posts and the locking bar to hold the latter in engagement with the former, said locking bar having laterally extending contact portions between the posts to rest against the follower block, the ends of said locking bar being spaced above the said follower block between the ends of the latter and said posts for insertion of an operator's finger beneath said ends of the locking bar when the posts are flexed to disengage the interlocking means.

6. In a binder of the character described, a pair of posts formed of relatively flexible material; a follower block provided with post-receiving openings; a locking bar having perforations therethrough to freely receive the posts respectively; and interlocking means formed on the posts and the locking bar to hold the latter in engagement with the former, said locking bar having laterally extending contact portions between the posts to rest against the follower block, the ends of said locking bar being spaced above the said follower block between the ends of the latter and said posts, said follower block having a cavity formed therein beneath each end respectively of the locking bar when the latter is in the operative position for insertion of an operator's finger in the cavity and beneath an end of the bar to lift said bar when the posts are flexed to disengage the interlocking means.
